(57) **CLAIM**

The ornamental design for a hair trimmer, as shown and described.

DESCRIPTION

FIG. 1 is a front perspective view of a hair trimmer showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 3;

FIG. 11 is a partial enlarged view of FIG. 4; and,

FIG. 12 is a partial enlarged view of FIG. 7.

The broken lines in the figures are for the purposes of illustrating portions of the hair trimmer, which form no part of the claimed design.

1 Claim, 6 Drawing Sheets
